[57] CLAIM

The ornamental design for a cursor control for computer display, as shown and described.

DESCRIPTION

FIG. 1 is a top, front perspective view of a cursor control for computer display showing my new design;

FIG. 2 is a top plan view thereof on a reduced scale;

FIG. 3 is a front elevational view thereof on a reduced scale;

FIG. 4 is a bottom plan view thereof on a reduced scale;

FIG. 5 is a rear elevational view thereof on a reduced scale;

FIG. 6 is a right hand side elevational view thereof on a reduced scale;

FIG. 7 is a left hand side elevational view thereof on a reduced scale;

FIG. 8 is a top, front perspective view thereof on a greatly reduced scale, the display and computer being shown in broken lines for illustrative purposes only.

FIG. 1

FIG. 2

FIG. 3

FIG. 4

FIG. 5

FIG. 6

FIG. 7

FIG. 8
